SASH PULLEY

Edwin W. North, Rockford, Ill., assignor to
National Lock Co., Rockford, Ill., a corpora-
tion of Delaware

Application May 31, 1930. Serial No. 458,572

4 Claims. (Cl. 16—212)

This invention relates to the construction and method of making sash pulleys and to a pulley that is particularly well adapted to be used in a relatively thin sash frame.

8 It is an object of this invention to provide a pulley of this nature which may be manufactured economically in large quantities and which is strong and durable.

In accordance with this invention the complete 10 pulley housing is made of two sheet metal parts, one the casing, preferably formed of one piece of sheet metal secured to the second, a face plate, formed from a second piece of sheet metal. It is also preferred to use an all metal pulley wheel 15 within the metal housing although any type of pulley wheel may be used satisfactorily within the housing.

A better understanding will be had of my invention from the following description given in 20 connection with the drawings in which:

Fig. 1 is a side elevation of a sash pulley constructed in accordance with this invention.

Fig. 2 is an end elevation of the pulley shown in Fig. 1 looking at the right hand end thereof.

25 Fig. 3 is a vertical section on line 3—3 of Fig. 1.

Fig. 4 is a section on line 4—4 of Fig. 1.

Fig. 5 is a section on line 5—5 of Fig. 1.

Fig. 6 is a plan view of a single blank from which the pulley casing is formed.

30 Fig. 7 is a plan view of the blank after one or more operations has been performed thereon.

Fig. 8 is a plan view during another stage of its formation.

Fig. 9 is a section on line 9—9 of Fig. 8.

35 Fig. 10 is a bottom plan view of the blank shown in Fig. 8.

Fig. 11 is an end elevation.

Fig. 12 is an end elevation looking into the casing after the blank has been formed.

40 Fig. 13 is a plan view of a blank partially formed comprising the face plate.

Fig. 14 is a plan view of the face plate completely formed, and

Fig. 15 is a section on line 15—15 of Fig. 14.

45 Fig. 16 is plan view of the strip from which the blanks shown in Fig. 6 are formed.

Referring to the drawings, the pulley housing can best be described by considering the steps involved in the method of manufacture thereof.

50 The complete housing comprises two members, one a casing for substantially inclosing the pulley wheel and the other a face plate for completing the enclosure and for securing the complete housing to the sash or other element to 105 which the housing is attached.

The casing member is formed from a single blank 1a shown in Fig. 6 which is first cut from a strip 1 shown in Fig. 16, the circular cut out portions being utilized for the sides of the pulley wheel. The blank 1a is then stamped by 60 suitable dies to bend the edge portions into flanges 2 and 3 extending at right angles from the body of the blank and to form the center portion 4 thereof to provide the two halves of the casing as shown in Fig. 7. The blank is then 65 further formed by punching and trimming to the form shown in Figs. 8, 9 and 10. At this stage the blank is in substantially complete form ready for folding. The center portion thereof is shaped to form the two halves 6 and 7 apertured as at 8 and 9 joined by the center portion 4 and terminating in the two flanges 2 and 3. The two halves are substantially bounded by slight beads or flanges 11 and 12.

The blank is also formed with a pair of ears 75 13 along one edge of the center portion 4 for purposes later to be described.

The blank is then bent or folded along the center portion 4 thereof to bring the two halves 6 and 7 together to provide a pulley chamber 80 therebetween with the flanges 2 and 3 opposing each other and lying in the same plane to form a continuous flat surface as shown more particularly in Fig. 12. When so formed the flanges 11 and 12 will abut each other thus providing 85 a strengthening rib around the periphery of the casing. Preceding or following the folding operation the flanges 2 and 3 may be trimmed to final shape as shown in Fig. 12.

Immediately after or during the folding operation the center portion may be provided with a depressed rib 14 (Fig. 1) which serves to keep the cord which passes over the pulley from contacting with the raw edge of the center portion 4, which, when the blank is fully formed, constitutes one outlet for the cord passing over the pulley. The prongs or ears 13 are also bent inwardly to form rope guides as shown in Fig. 1 to 90 guide the rope outwardly when it is being threaded over the pulley.

100 The face plate is also stamped from a single blank as shown in Figs. 13, 14, and 15. Fig. 13 shows the first operation at which operation the blank 15 is punched to provide a center depression 16. Upon further operation the blank is 105 stamped to provide a marginal flange 18 bent at right angles to the main body of the blank. The depression 16 is also apertured as at 19 and provided with a struck-in bead 20. The aperture 19 will permit passage of the cord which passes 110

over the pulley whereas the bead 20 will prevent the cord or rope from coming into contact with the raw edge of the metal surrounding the aperture. The casing and face plate may be provided 5 with apertures to receive securing screws.

When assembled a suitable pulley such as a sheet metal pulley 21 is inserted in the casing and secured therein by a pivot pin 22. The face plate is then placed over the flanges 2 and 3 with 10 the depression 16 projecting outwardly. The marginal flange 18 is then crimped about the outer periphery of the flanges 2 and 3 thus holding the casing together without the use of prongs or tongues.

It follows from the above that there has been 15 provided a sheet metal pulley housing composed of a casing member formed from a single sheet and which substantially surrounds the pulley when assembled and a face plate formed from a second blank and secured thereto without the 20 use of struck-up prongs engaging apertures in the casing member. The pulley housing may be economically manufactured in great quantities and when assembled occupies a minimum space 25 without sacrificing strength and rigidity.

It is obvious that minor changes may be made 30 in the details of construction without departing in the spirit and scope of this invention as defined in the claims appended hereto.

I claim:

1. A sash pulley housing comprising a casing, 35 said casing being formed from a single sheet of metal shaped and bent along a line intermediate

its ends to provide a recess for receiving and substantially inclosing a pulley, said ends terminating in a pair of flanges lying in the same plane, said casing having an opening provided therein for permitting the passage of a cord, and 80 a face plate formed from a second sheet of metal and secured to said flanges, said face plate having an opening therethrough for permitting the passage of a cord.

2. A sash pulley housing comprising a casing 85 formed from a single sheet of metal having two opposed circular portions connected by an integral relatively narrow strip of metal, said circular portions terminating in a pair of abutting flanges lying in the same plane, and a face plate secured to said pair of flanges.

3. A sash pulley housing comprising a casing 90 formed from a single sheet of metal having two opposed circular portions connected by an integral relatively narrow strip of metal, said circular portions terminating in a pair of abutting flanges lying in the same plane, and means for securing said flanges together.

4. A sash pulley housing comprising a casing 95 formed from a single sheet of metal having two opposed circular portions connected by an integral relatively narrow strip of metal, said circular portions terminating in a pair of abutting flanges lying in the same plane, and a face plate co-extensive with said pair of flanges and having 100 its peripheral edges crimped over said flanges.

EDWIN W. NORTH.
